UNITED STATES PATENT OFFICE.

CHARLES G. SMITH, OF MEDFORD, MASSACHUSETTS, ASSIGNOR, BY MESNE ASSIGNMENTS, TO RAYTHEON MANUFACTURING COMPANY, OF CAMBRIDGE, MASSACHUSETTS, A CORPORATION OF MASSACHUSETTS.

PRODUCTION OF ELECTRICAL VARIATIONS.

Application filed May 3, 1921, Serial No. 466,518. Renewed January 11, 1927.

The present invention relates to a method and apparatus for producing variations in electrical energy and is more particularly concerned with the type of apparatus disclosed in the copending applications of Smith Serial No. 415,536, filed October 8, 1920, and Serial No. 418,263, filed October 20, 1920.

As disclosed in the applications above referred to, the employment of curved electrodes immersed in a gas with all available paths for conduction through the gas short and of the order of magnitude of the mean free path of the electrons and with all paths through the insulating medium sufficiently long to prevent breakdown and with a magnetic field introduced in the space separating the surfaces of the electrodes at different potentials permits conduction to freely take place between the surfaces of the electrodes in one direction but not in the opposite direction, thus affording a simple and convenient means for the rectification of alternating currents. The ability of such a device to successfully rectify depends, as stated, upon the separation of the electrodes and in addition upon the strength and character of the magnetic field and the pressure of gas in which the electrodes are immersed.

It has been discovered that if the lines of force of the magnetic field are curved and concave toward the cathode the electron discharge is localized and concentrated in a manner to markedly improve the rectifying qualities of the apparatus, more particularly by greatly increasing the permissible range of magnetic field over which rectification can take place.

In one form of the invention a magnetic field is introduced between two electrodes with curved lines of force extending lengthwise of the electrodes and concave toward one of the electrodes in such a manner that the lines of force intercept the surface of this electrode at two points spaced lengthwise of the electrode. With such a construction and with an electric field created between the electrodes, conduction takes place when the electrode, with respect to which the lines of force are concave, acts as the cathode and the gap becomes insulating when the opposite electrode, or the one with respect to which the lines of force are convex, acts as the cathode. Moreover the

conduction tends to become concentrated or bunched in the region beneath the center of the arches formed by the curved lines of force. The region in which conduction is concentrated may be indicated approximately by a radial plane intersecting the arches of the lines of force at approximately their central points.

Referring to the accompanying drawings Fig. 1 represents a section in elevation of a tube embodying the principles of the invention, and Fig. 2 is a diagrammatic view illustrating the tube employed as a rectifier in a simple circuit.

The tube shown in the illustrated embodiment of the invention comprises a gas filled receptacle 10 of suitable form having cooperating cylindrical electrodes 12 and 13 received therein. The electrode 12 is supported concentrically within the receptacle by supporting members 14 which extend from the inner surface of the electrode to a base portion 16 forming a part of the receptacle. The cooperating electrode cylinder 13 is supported in a like manner by members 18 which extend to a base portion 20 formed in the opposite end of the receptacle 10. The two electrodes are designed with respect to one another in such a manner that all paths available for conduction through the gas are short and all paths through the insulating medium are sufficiently long to avoid breakdown. The inner electrode cylinder 12 is connected with a lead 22 passing outwardly through the base 16 and the outer electrode cylinder 13 is connected with a lead 24 passing outwardly through the base 20 at the opposite end of the receptacle.

A magnetic field of suitable strength and having its lines of force curved and concave with respect to the outer electrode is introduced into the space separating the two electrodes to cause gaseous conduction to take place when the outer electrode is negative and to prevent gaseous conduction when the inner electrode is negative. This magnetic field may be conveniently supplied by annular pole pieces 26 and 28 which encircle the receptacle 10, as indicated, the magnetic field being created in the space between the upper and lower pole pieces. A plurality of permanent magnets 30 and 32 operate in conjunction with the pole pieces

2

to supply a magnetic field having lines of force extending generally as indicated in dot and dash lines. With this construction and with the outer electrode acting as a cathode, gaseous conduction freely takes place between the surfaces of the electrodes and is largely concentrated in the region beneath the center of the arches. On the other hand, with the inner electrode acting as a cathode the tube insulates against high voltages and conduction cannot take place.

The theory underlying this type of construction is believed to be essentially as follows: When the outer cylinder, toward which the lines of force are concave, acts as the cathode electrons starting from a region adjacent the upper or lower portions of the cylindrical cathode are deflected by the magnetic field toward the center, these electrons in general producing a positive ion nearer the center of the arches than their points of origin. These positive ions dropping to the cathode liberate more electrons which in turn are deflected toward the center of the arches, this process being repeated until the discharge is concentrated in the region adjacent the radial plane indicated by dot and dash lines. Electrons liberated in this plane are not deflected either above or below it but tend to liberate ions in the plane of origin. It will thus be obvious that the discharge tends to build up with the greatest intensity in the region immediately adjacent to the meridian plane. On the other hand, electrons leaving the inner cylinder when the latter acts as a cathode are dispersed and dissipated away from the center of the arch by the curvature of the magnetic field to a region of lesser magnetic field so that positive ions liberated by the impact of these electrons in turn liberate electrons in a region of small magnetic field and there is no tendency for a continued discharge to take place. It should be understood that the curvature or distortion of the path of the electrons lengthwise of the electrodes by a magnetic field of the character described is in addition to and apart from the distortion of the path of electrons by the magnetic field in planes extending radially of the electrode members, as previously described in certain of my other copending applications. The introduction of a uniform or non-symmetrical magnetic field between two electrodes tends to cause rectification but does not necessarily tend to localize or concentrate the conduction in a single plane as is the case with the present construction.

Fig. 2 illustrates a simple form of circuit embodying the tube as a rectifier, this circuit comprising an input circuit indicated at 40 capable of delivering alternating current to the primary of a step-up transformer 42, the secondary of which is embodied in an output circuit containing the tube which

rectifies the high voltage alternating current delivered thereto. This output circuit may be connected with any desired form of load circuit (not shown) to utilize the high voltage current so rectified.

Although the illustrated embodiment of the invention is shown in a tube having the lines of force of the magnetic field curved with respect to the electrode surfaces, it should be understood by those skilled in the art that the broader principles of the invention are susceptible of embodiment in any tube designed to cause the cathode surface to be intersected at a plurality of points by the lines of force of the magnetic field, as for example a tube having a curved cathode surface intersected at a plurality of points by the lines of force.

The radial surface of electrode 12, which extends outwardly from the diameter of the smaller active portion of electrode 12 to the diameter of the outer tubular electrode 13 intermediate the reentrant stem 16 and the space between the two electrodes where the electrical discharge occurs, together with the peripheral surface which extends lengthwise of the tube from the outer edge of said radial surface in close juxtaposition to the wall of the tube, with a thin gas space between the peripheral surface and the tube wall, protects that portion of the tube where the conductor 22 enters the tube from the electrical discharge and the radiation of light and heat therefrom.

I claim:

1. An electrical apparatus, comprising inner and outer electrodes immersed in a gas, means for creating an electric field between the surfaces of the electrodes, and means for introducing a magnetic field between the electrodes, having the lines of force between the electrodes curved and concave toward the surface of the outer electrode.

2. An electrical apparatus, comprising a hermetically sealed gas-filled tube, inner and outer electrodes of circular cross-section supported in concentric relation within the tube, means for creating an electric field between the surfaces of the electrodes, and means for introducing a magnetic field between the electrodes, having the lines of force curved and concave with respect to the surface of the outer electrode.

3. An electrical apparatus, comprising a hermetically sealed gas-filled tube, inner and outer electrodes of circular cross-section positioned within the tube, means for creating an electric field between the electrodes, and means for introducing a magnetic field between the electrodes, comprising annular pole pieces surrounding the outside of the receptacle and spaced apart lengthwise of the electrode.

4. An electrical apparatus comprising co-

operating electrodes immersed in a gas, means for creating an electric field between the surfaces of the electrodes, and means for introducing a curved magnetic field between the electrodes having the lines of force cutting one electrode and arranged to concentrate ionization in a region restricted longitudinally of the electrodes.

5. An electrical apparatus comprising co-
10 operating electrodes immersed in a gas, means for creating an electric field between the surfaces of the electrodes, and means for introducing a magnetic field between the electrodes with the lines of force extending
15 in such a manner and of such a character that ionization is dissipated with one of the electrodes acting as the cathode.

6. An electrical apparatus comprising electrodes immersed in a gas and having
20 opposing surfaces separated by a distance which is short and comparable to the mean free path of electrons in the gas, means for introducing a magnetic field between the electrodes, the magnetic field and the electrode surfaces being curved relatively to one another.

7. An electrical apparatus comprising a gas filled receptacle, means for impressing an electric field in a portion of the gaseous
30 region limited in length to a distance comparable to the mean free path of electrons in the gas, and means for introducing a magnetic field in the gaseous region having the lines of force curved.

35 8. An electrical apparatus comprising electrodes immersed in a gas and separated by a distance comparable to the mean free path of the electrons in the gas, and means for introducing a magnetic field between the electrodes with the lines of force cutting one of the electrode surfaces at a plurality of points.

40 9. An electric discharge tube having a re-entrant stem, a tubular electrode having one end directed toward said stem, an electrode surface presented to the interior of said

tubular electrode, a conductor extending through said stem for conducting current to said surface, and a surface extending transversely of the axis of said tubular electrode between said electrode surface and said reentrant stem, said surface extending outwardly from a diameter substantially confined to that of said electrode surface to a diameter at least substantially as great as that of the opening in the adjacent end of the tubular electrode and a surface extending lengthwise of the tube from the outer edge of said transverse surface.

50 55 10. An electrical discharge tube having a reentrant stem, a tubular electrode having one end directed toward said stem, an electrode surface presented to the interior of said tubular electrode, a conductor extending through said stem for conducting current to said surface, an annular metallic surface presented to the space between said tubular electrode and said electrode surface intermediate said stem and said electrode surface, said annular surface having a radial dimension at least approximately as great as the difference in diameters between said tubular electrode and said electrode surface, and a surface extending lengthwise of the tube from the outer edge of said annular surface in close juxtaposition to the inner surface of the tube.

60 65 70 75 80 85 11. An electrical discharge device having a reentrant stem, an electrode opposite said stem, a smaller electrode surface between said stem and electrode, a shielding surface intermediate said stem and electrode surface, said shielding surface extending outwardly from a diameter substantially confined to that of said electrode surface to a diameter at least substantially as great as that of said electrode, and another shielding surface extending longitudinally of the tube from the outer edge of said shielding surface, the longitudinal surface being surrounded by a thin gas space.

CHARLES G. SMITH.
